UNITED STATES PATENT OFFICE.

JOHN W. FREE, OF RICHMOND, INDIANA.

IMPROVED WASHING-MACHINE.

Specification forming part of Letters Patent No. 40,682, dated November 24, 1863.

To all whom it may concern:

Be it known that I, JOHN W. FREE, of Richmond, in the county of Wayne and State of Indiana, have invented a new and useful Washing-Machine; and I do hereby declare the following to be a full, clear, and exact description of the same, reference being had to the annexed drawings, making a part of this specification, in which—

Figure 1 is a vertical view of the machine with the top board, J, removed. Fig. 2 is a section of the machine. Fig. 3 is a perspective view of the machine. Fig. 4 is a view of the strip of half-round india-rubber that is fastened on at the lower side of wash-board D.

Similar letters of reference indicate corresponding parts in the different figures.

To enable those skilled in the arts to fully understand and construct my invention, I will proceed to describe it and its operation.

A represents a box or case, which may be constructed in the form shown at Fig. 3, to receive and hold the working parts of the machine. B is a roller or cylinder to which the handles, and also the wash-board D and hinged half-round piece of india-rubber or gutta-percha, E, is attached. C is the handle to the machine. E is a piece of india-rubber or gutta-percha. F is a wash-board placed in the back part of the machine. G is the pinions to the roller B. H is the hinge on which the rubber works. I is a staple working in the

hinge H. J is the top of the box A. K is a space between the wash-boards D and F.

The operation of the machine is as follows: The box A, being partly filled with water, the clothes to be washed are placed in the open space K, when the handles C are pressed downward, thus forcing the wash-board D and semicircular piece E in a forcible manner against the clothes, and causing the water to rush around at the ends of the wash-board D. The wash-board F being held in a firm position, the clothes are forced over its entire surface at each downward motion of the handles. The handles being raised releases the clothes, when they will fall back upon the bottom of the box A, when the operation being repeated the clothes will soon be washed, as the piece E produces a soft, yielding, rolling, squeezing, rubbing surface to the clothes.

Having thus described the nature, construction, and operation of my invention, what I claim therein as new and useful, and desire to secure by Letters Patent, is—

The piece E, in combination with the wash-boards F and D, roller B, handles C, and hinges H, when arranged, constructed, and operated for the purpose and in the manner set forth.

JOHN W. FREE.
